UNITED STATES PATENT OFFICE.

BRICE PHANDERS SWYERS, OF PITTSBURGH, PENNSYLVANIA, ASSIGNOR TO MOTORS
LOCK COMPANY OF AMERICA, OF PITTSBURGH, PENNSYLVANIA, A CORPORATION
OF DELAWARE.

LOCK-SWITCH.

1,339,302.

Specification of Letters Patent.

Patented May 4, 1920.

Application filed March 5, 1919. Serial No. 280,767.

To all whom it may concern:

Be it known that I, BRICE PHANDERS SWYERS, a citizen of the United States, and resident of Pittsburgh, in the county of Allegheny and State of Pennsylvania, have invented a new and useful Improvement in Lock-Switches, and I do hereby declare the following to be a full, clear, and exact description thereof.

10 My invention pertains to electric ignition lock switches, and relates more particularly to lock switches for use in connection with automobiles, to prevent unauthorized running of the engine or tampering 15 with the same. It is the principal object of my invention to improve upon ignition locks or lock switches of this class. It is another object of my invention to provide a lock switch of the permutation type, which 20 will be of a simple and compact construction and easy to manufacture, and which will render it impossible to complete the necessary circuit for running the engine without previous knowledge of the combination. 25 Other and further objects of my invention will appear from the following description and be illustrated in the accompanying drawings.

I have described, by way of example, in 30 the following specification, and shown in the accompanying drawings, one form of lock constructed in accordance with my invention. I wish it understood, however, that the invention may be embodied in other 35 forms, and that changes may be made in the form which is described and shown, without exceeding the scope of the invention, as defined in the appended claims.

In the drawings:—

40 Figure 1 is a circuit diagram, also showing face views of the contacts employed in the switch;

Fig. 2 is a top plan view of my device;

Fig. 3 is a side view having the casing 45 broken away;

Fig. 4 is a cross-sectional view through the center of the device;

Fig. 5 is a top plan view of the rotatable hub with the contacts thereon;

50 Fig. 6 is a bottom plan view thereof;

Fig. 7 is a plan view of the hub;

Fig. 8 is a view on the line 8—8 of Fig.

7, and

55 Figs. 9 to 13 are detailed views of different portions of the device.

Referring now particularly to the drawing, the lock switch comprises two insulating disks 2 and 3 placed one above the other, the disks being held in spaced relation by means of three metallic standards 4. The 60 disks are surrounded by a casing 5, which is closed at the top by a glass 6. Mounted on top of the disk 3 is a dial 7. Rotatably mounted on the disk 2 is a spindle 8 having a squared portion 9 upon which is mounted 65 an insulating hub 10. The hub 10 has mounted on the top side thereof a contact arm 11, said arm being rotatable with respect to the hub within limits bounded by stop pins 12, which are rigid in the hub 70 and extend through slot 13 in said arm 11, and a corresponding slot in washer 13'. A contact arm 14 is mounted similarly on the bottom side of the hub 10 but is limited by but one stop pin 15. 75

The disk 2 carries on its upper face an outer contact strip 16, such strip being in the form of a circle having a short portion broken out therefrom. At the center of the broken out portion is a contact 17 provided 80 with a concave face. A similar contact strip 18 of smaller diameter is mounted within the strip 16, and a contact 19 similar to the contact 17 is mounted at the broken part of the strip 18. 85

The under side of the disk 3 carries similar strips 20 and 21, and contacts 22 and 23 placed in the broken part of the respective strips.

The contact strips have their upper face 90 corrugated and have their side faces extending outwardly forming a dove-tailed body portion.

The contacts 23 and 19 have integral posts 24 and 24^a extending down through the disk 95 2. The contacts 17 and 22 are joined.

The outer strips are in circuit through connections 25 and grounded through one of the standards 4, and casing 5.

The inner strips are in circuit through 100 connections 26, and the inner strip 18 is connected to the magneto ground through post 27.

The spindle 8 extends upwardly through the glass cover 6 over the dial 7 and has 105 a knurled knob 28, having a hand or pointer 28'.

In setting the combination of the lock switch the knob 28 is first turned in one direction until the contact arm 14 is in en- 110

gagement with the contacts 17 and 19 and then reversed until the contact arm 11 is in engagement with the contacts 22 and 23; the circuit will then be complete from the 5 battery through post 24, through contact 23, contact arm 11, contact 22, contact 17, contact arm 14, contact 19 to the locks or other mechanism 30 to be operated.

The correct position of the contact arms 10 11 and 14 correspond to certain numerals of the combination on the dial 7. The position of the contacts 11 and 14 is designated by the hand or pointer 28'.

When the contact arms are in any other 15 position than in engagement with the contacts 17, 19, 22 and 23, the battery circuit will be broken and the ground magneto circuit will be closed since the contact arm 11 will extend across the rings 20 and 21, and 20 the contact arm 14 will extend across the rings 16 and 18, or either contact arm may remain in engagement with the contacts in the broken part of the rings while the other arm is across the rings according to 25 the amount of movement of the knob 28.

It will be seen from the above that the lock switch of my invention is of an exceedingly simple construction, and combines all the necessary parts in one device. The 30 lock-switch takes up no more room in a car than a dash speedometer or clock; and the construction is such that it is impossible for anyone, either by listening or otherwise, to find out the combination of the switch. 35 The device does away with the necessity of carrying keys; all that is necessary being to turn the combination.

Having thus described my invention, what I claim is:

40 1. A lock switch comprising two disks spaced one above the other, contact rings on said disks, a shaft mounted to rotate with respect to said disks, other contacts on said disk and insulated from said rings, contact 45 arms revolvably mounted on said shaft, said arms having limited movement relative to said shaft, one of said arms having a greater restricted movement than the other, and means for moving said contact arms to desired positions.

50 2. A lock switch comprising a casing, two disks spaced one above the other, contact rings, having broken out portions, on said disks, a shaft mounted to rotate with respect 55 to said disks, other contacts on said base within said broken out portions of said rings, a bushing on said shaft, contact arms revolvble with respect to said bushing and carried thereby, said arms having a restricted movement relative to said bushing, one of said arms having a greater restricted 60 movement than the other, and means for rotating said shaft and said arms.

3. A lock switch comprising a casing, two disks spaced one above the other, contact 65 rings having a portion broken out therefrom mounted in said disks, other contacts mounted in said disks, a shaft mounted to rotate with respect to said disks, a bushing fixedly secured on said shaft, contact arms 70 revolvble with respect to said bushing and carried thereby, said arms having a restricted movement relative to said bushing, one of said arms having a greater restricted movement than the other, a dial on the top 75 of said casing, means for rotating said shaft and said contact arms, and means coöperating with said dial for designating the location of said arms.

4. A lock switch comprising a casing, two 80 insulating disks spaced one above the other, contact rings having serrated top faces mounted in said disks, said rings having portions broken out therefrom, other contacts having concave top faces mounted in 85 said disk, a shaft mounted to rotate with respect to said disks, a bushing of insulating material fixedly secured on said shaft, contact arm mounted on said bushing and revolvble with respect thereto, said arms having convex contacting ends adapted to engage in the serrations in said rings and in said concave faces of said contacts, said arms having a restricted movement, relative to said bushing, one of said arms having a 90 greater restricted movement than the other, a dial on the top of said casing, means for rotating said shaft and said contact arms, and means coöperating with said dial for 95 designating the location of said arms. 100

5. In a lock switch of the class described, a plurality of disks, each of said disks having inner and outer contact rings having portions broken out therefrom, said rings having dove-tailed body-portions, and serrated top faces, substantially as described. 105

6. In a lock switch of the class described, a plurality of disks of insulating material, each of said disks having inner and outer contact rings having serrated upper faces, 110 said rings extending above the face of said disks and having portions broken out therefrom, portions of said disks extending above the plane of said disk on a line with said rings, said portions of said disk being serrated, and said rings being held in position by dove-tailed body portions, substantially as described. 115

In testimony whereof, I, the said BRICE PHANDERS SWYERS, have hereunto set my 120 hand.

BRICE PHANDERS SWYERS.
